[57] CLAIM

The ornamental design for a game housing, substantially as shown and described.

DESCRIPTION

FIG. 1 is an isometric view showing the right side and the top of my new design for a game housing;

FIG. 2 is a left side elevational view thereof;

FIG. 3 is a rear elevational view thereof;

FIG. 4 is a bottom plan view thereof;

FIG. 5 is an isometric view similar to FIG. 1, differing from FIG. 1 with regard to a surface located within the interior of the transparent housing;

FIG. 6 is an isometric view similar to FIG. 1, differing from FIG. 1 with regard to a surface located within the interior of the transparent housing;

FIG. 7 is a right side elevational view of the housing of FIG. 6.

FIG. 1

FIG. 2

FIG. 3

FIG. 4
